BRUSH HANDLE CONNECTION

Eugene C. Rackliffe, Jackson, Mich.

Application May 22, 1948; Serial No. 28,630

3 Claims. (Cl. 306—3)

1.

This invention relates to hand brooms as employed to sweep floors or other surfaces.

The invention has for its object to provide an improved broom construction by which the handle is capable of being adjustably connected with the broom head to enable the latter and the handle to be set at will at any desired relative angular position, and this in a simple and rapidly accomplishable manner and while providing also for the obtaining of an angularly fixed condition of the broom head and handle relatively to one another when this is desired.

In one form, the invention provides a broom head having a central opening in which a through bolt can be accommodated for the releasable attachment of either of two separate handles, both of which have an end portion with which said through bolt is engageable to secure the handle upon the said head (the latter having the conventional bristles extending from its underneath surface) and one of which handles has its said end portion also formed for relative engagement with the head so as to secure the handle and head in a set relative angular position, whereas the other handle has its end portion so formed for engagement with said bolt as to permit the said relative angular position to be varied at will. In such form of the invention the two handles are alternatively employed in association with the same broom or brush head, depending upon whether a fixed or adjustable angular positioning of the head and handle is required.

In another form, the invention provides a broom head having a central opening in which a through bolt can be accommodated for the releasable attachment of a handle having an end portion provided with a pair of longitudinally spaced openings, in either of which the said through bolt is optionally engageable and which are employed in association with a separate plate member also having an opening with which the through bolt is engageable and also formed to have relative engagement with the broom head to secure the latter against angular movement relatively to the handle when the through bolt is engaged with said handle opening as well as with the registering opening in the plate member. The arrangement is such that when the handle end is positioned to cause the through bolt to engage in one opening therein, as well as the opening in the plate member, relative angular adjustment of the handle and head is possible, whereas when the handle end is positioned to cause the through bolt to engage the other opening therein, as well as the plate open-

2.

ing, the handle and head are secured against such relative angular adjustment.

The invention will appear clear from a consideration of the following detailed description of two practical embodiments of the invention given by way of example and with reference to the accompanying drawings in which:

Fig. I is a perspective view of one embodiment, with the handle shown broken away for ease of illustration and the handle end constructed to secure the handle and broom head against relative angular adjustment, the securing through bolt being also omitted from this view for ease of illustration.

Fig. II is a fragmentary view of the handle of Fig. I, showing the construction of the head engaging end portion thereof.

Fig. III is a similar view to Fig. II but of an alternative handle end construction, which can be employed with the same broom head when it is desired that relative angular adjustment of the handle and head should be possible.

Fig. IV is a fragmentary plan view of the broom head with the handle of Fig. III shown attached thereto and the handle adjusted to two extreme angular positions as shown in dotted lines.

Fig. V is an exploded perspective view of the second embodiment of the invention, with the handle broken away for ease of illustration.

Fig. VI is a cross section on the line A—A of Fig. VII showing the head, plate, bolt and handle construction, as seen in Fig. V, secured together to provide the possibility of the handle and head being angularly adjusted relatively to one another.

Fig. VII is a plan view of Fig. VI, with the broom head shown broken away for ease of illustration and the handle shown in dotted lines in two possible alternative adjusted positions.

Fig. VIII is a cross section on the line B—B of Fig. IX, showing the parts so connected as to preclude the possibility of the handle and head being angularly adjusted.

Fig. IX is a plan view of Fig. VIII, and

Fig. X is a cross-section on the line C—C of Fig. IV.

Referring to the drawings and first to Fig. I to IV and X, the embodiment of the invention shown therein involves the use of a common broom head 1 having the conventional bristles 2, and either of two handles 3 or 4, of which the handle 3 is formed at one end for engagement with the broom head to preclude relative angular adjustment of the head and handle, whereas the

other handle 4 is formed for connection with the head 1 so as to permit such angular adjustment to be effected at will.

The broom head is formed with a central vertical bore 5 through which a bolt member 6 is capable of being passed and with the upper end of which bore an opening 7 in a cranked plate 8 is capable of being registered to permit the upper and screw-threaded extremity of the bolt to extend above the plate and serve for the attachment of a wing or equivalent nut 9, whereby the bolt head (not shown) lies within the mass of bristles 2, and against the underneath surface 10 of the broom head, and the bolt and nut serve to releasably secure the handle upon the broom head.

The cranked plate 8 of the handle construction according to Fig. I and II is formed at its one extremity with a depending lip 11 which engages in a recess 12 formed in the upper surface of the broom head and serves to secure the head and handle against relative angular adjustment when the nut 9 is tightened into operative position.

When it is desired to employ the broom head with the possibility of the relative angular position of the head and handle being adjusted, the alternative handle 4 of Fig. III and IV is employed in place of the handle 3. The handle 4 also has a cranked but lip-less plate 13, whereby the plate presents a flat surface 14 to the upper surface of the broom head and by loosening the wing nut 9 permits the handle to be adjusted to any required angular position relatively to the broom head. Thus the handle can be secured to extend perpendicularly to the longitudinal axis of the broom head, as is usual with fixed broom handle constructions and as is shown in the full line handle position of Fig. IV, or the handle can be swung to either dotted position, as shown in Fig. IV, and in either of which positions the broom handle extends in the direction of said longitudinal axis and permits the broom to be correspondingly operated. That is to say, with the handle position thus adjusted the sweeping operation would be performed with the brush operating endwise. Other angular positions are, of course, possible between said full line and dotted positions.

Referring now to the second embodiment of the invention, as shown in Fig. V to IX, in this embodiment either an angular adjustable or fixed angular positioning of the handle relatively to the broom head is obtainable with the same handle 14 in association with a separate plate member 15 having a depending lip 16 at one extremity and an opening 17 through which the securing bolt 18 can be passed. In this construction also the broom head 19, having the conventional bristles 20, has a central vertical bore 21 through which the bolt 18 is capable of being passed to position its head 22 against the underneath surface of the broom head and its screw-threaded extremity 23 beyond the upper surface of the head for the attachment of the securing wing or equivalent nut 24. A spring washer 22a can be employed in association with the nut head 22 to secure the required connection of the broom handle and broom head.

The handle 14 has a cranked plate 25 secure at its one extremity, which cranked plate, as in the case of the previously described cranked plates 8 and 13, provides that the handle proper is inclined to the broom head when secured upon the latter and provides also a flat end portion 26 having a pair of longitudinally spaced openings 27 and 28, either of which serves for the passage of the bolt 18. The plate 15 also has the single opening 17,

previously mentioned; which opening serves also for the passage of the bolt, with the plate positioned to overlap the plate portion 26 and the depending lip 16 engaged in a recess 29 in the top surface of the broom head 19.

To use this second embodiment of the invention, to permit the relative angular position of the broom head and handle to be varied at will with the handle retained upon the broom head, the handle 14, plate 15, and broom head 19, are connected together by the bolt 23 and nut 24, as shown in Figs. V, VI and VII. In this connected condition, the bolt 23 passes through the opening 28 in the cranked handle end plate 25 as well as through the registered opening 17 of the overlying plate 15. In this connected condition, therefore, and as shown clearly in Figs. VI and VII, there is sufficient clearance 30 between the end edge 31 of the handle end plate 25 and the depending lip 16 as to permit angular movement of the handle and plate 25 relatively to the broom head to be effected when the nut 24 is slackened. Thus, the handle can be swung from its full line position as shown in Fig. VII to either of the dotted line positions as shown in this figure, as well as to intermediate angular positions.

If, however it is desired that the handle and broom head should be connected together in fixed angular relationship the connection of the parts is as shown in Figs. VIII and IX. In this connected condition the bolt 18 is passed through the opening 27 of the cranked handle end plate 25, with the result that the clearance 30 is taken up and the end edge 31 is brought up against the depending lip 16, as shown clearly in Fig. VIII. Accordingly, angular adjustment movement of the handle 14 is precluded.

In both embodiments of the invention provision is made whereby the depending lip 11 or 16 can be engaged respectively in either the recess 12 or 29, or in an alternative recess 32 on the opposite side of the broom head surface. This permits the broom handle to be secured in position upon the broom head so that it is directed away to the right or left of the broom head. In this way compensation may be made for wear on the bristles 2 or 20 due to the sweeping operation taking place continuously in the same direction.

Having thus described my invention, what I claim as novel and desire should define the scope of the required patent protection is as follows:

1. In combination, a broom head having a bolt receiving opening therein, a separate handle the inner end of which is provided with a pair of longitudinally spaced openings either of which is capable of being registered with said bolt opening, a separate anchor plate having an opening therein also capable of being registered with said bolt opening with the said anchor plate and broom head held against movement relatively to one another, and a bolt member adapted to be received in said registered openings to secure the handle upon the broom head with the said plate either permitting or preventing relative angular adjustment of the broom head or handle, depending upon whether the bolt is engaged in one or the other of said pair of openings in the said handle end.

2. The combination as claimed in claim 1 in which said broom head is formed with a recess in its upper surface and in laterally spaced relationship to said bolt opening and the said anchor plate is formed with a depending lip engageable in said recess to hold the plate and broom head

against relative movement when the anchor plate is secured in operative position by said bolt, with the latter engaged in said plate opening, said lip forming an abutment for the said handle end portion to prevent angular movement of the handle relatively to the broom head when the handle is secured upon the broom head with the bolt engaged in that one of the said pair of openings which is remote from said lip.

3. An angularly adjustable broom head and handle assembly comprising a broom head having a lower bristle supporting surface and an upper surface upon which the handle is adjustably clamped, a threaded bolt member having the head portion engaging with said lower surface and extending upwardly through said head to provide a threaded stud portion extending through and above said upper surface, a handle having at its lower end a flat metal member angularly disposed to the longitudinal axis of the handle to permit the same to rest flat upon said upper surface, a hole defined in said metal mem-

ber to freely receive said stud portion, a separate clamping plate having a hole to receive said stud portion and disposed above said metal member, said plate having a downwardly directed projection spaced from the hole defined therein, an opening defined in said upper surface to receive said projection to hold said plate against rotation upon said stud portion, and a clamp member threaded upon the upper end of said stud to engage said plate to adjustably clamp said metal member for relative angular movement between said plate and said upper surface.
